HANDBAG FRAME

Edward Poeter, Irvington, N. J., assignor to E. Poeter & Co. Inc., Irvington, N. J., a corporation of New Jersey

Application March 7, 1936, Serial No. 67,618

1 Claim. (Cl. 150—29)

This invention relates to handbag frames, and has for its purpose and object the provision of a special frame which when used in the making of a handbag, permits the insertion therein of pocket portions for various accessories such as a cigarette case, vanity case, and the like. In the present type of handbag these accessories, as now generally used, cause the handbag to bulge along its flexible walls and in consequence an unsightly appearance is the result.

The frame of the present invention is so constructed as to provide a large space in the upper part of the handbag, this being made possible by reason of the wide walls utilized and forming part of the handbag frame.

This handbag frame may be made in several ways, either by attaching to the basic walls, U-shaped members for the insertion therein of the ends of the flexible material forming the handbag, or by forming the basic walls themselves into such U-shaped portions in which the ends of the flexible material of the handbag may be inserted and secured.

The invention consists further in an improved hinge for handbags of this character which is constructed so as to give the greatest amount of resistance resulting from constant use of the handbag.

With the above and other objects in view, the invention will be more fully described herein-after, and more fully brought out in the subjoined claims.

In the drawing, wherein similar reference characters refer to corresponding parts throughout the several views:—

Figure 1 is a perspective view of my improved handbag frame embodied in a hand bag and partially shown;

Figure 2 is a vertical section taken on the line 2—2 of Figure 1;

Figure 3 is a section taken on the line 3—3 of Figure 1; and

Figure 4 shows an alternative structure embodying the invention and in partial perspective view of one section of the frame only.

Referring to the drawing and more particularly to Figure 2, the base frames designated as 10 extend along the top of the bag and depend at each end thereof into lateral members of the same width, indicated at 11. At their free ends these lateral members 11 are hinged by means of a hinge 12 which permits opening and closing of the bag in usual manner. Within these U-shaped base members 10 and their depending lateral members 11, U-shaped members 13 are pro-

vided the upper edges 14 of which are secured to the free edges 15 of the base frame members 10 in such manner that the extreme edge of the base frames 10 and extreme edge of the members 13 are in line with each other, as shown in Figure 5. These U-shaped members 13 may be secured to the base frame members 10 by soldering or the like which will hold them as they extend around the base members 10, including the lateral portions 11 thereof, as shown in Fig. 1. It will be particularly noted that the depth of the U-shaped members 13 is relatively small and because of this they do not extend very far into the space immediately beneath the base frames 10, and this gives a large space between the inward walls 15 of the oppositely placed U-shaped members 13 and the base frames 10 indicated by the reference character 16.

In a manner well known in this art, the free edges of the bag material designated as 17, are first inserted into a metal clip 18 and then folded upon themselves and in this turned over manner they are inserted into the cavity of the U-shaped members 13, as shown in the left-hand side of Fig. 2. The clip 18 is so disposed with respect to the parts 14 and 15 that the flexible bag material extends slightly upward in curved form against the portion 14, shown in Fig. 2, all of which gives the bag a finished appearance.

Within the flexible material of the bag, pockets 19 and 20 made of lining or other material are secured to the inner lining of the bag and these pockets are adapted to hold a cigarette case as 21, a vanity case as 22, or other necessities if desired, as shown in Fig. 2.

The bag frames are fastened by a suitable locking device indicated by reference character 23. It will be particularly noted that the depending portions of the U-shaped members 13 are close to the outer edges of the base frames 10 which peculiar construction gives a large interior space as hereinbefore stated, and upon the insertion of a cigarette case, a vanity case, or other accessories, the bag is not expanded beyond its initial shape; and even though it may contain several accessories the correct form of the bag is maintained and bulging or an unsightly appearance as is often the case in the present form of bags, eliminated.

In Figure 3, the hinge 12 is shown in section. This hinge 12 consists of two members 30 and 31 each having an opening through which a pivot pin 32 upsets, and also has an ornamental button or the like, as indicated by 34. These two frame members 30 and 31 are hinged to the pin 55

32 and each of these members 30 and 31 has a cut-out portion 35, and when the frame is assembled these two members slide along the free surfaces of the two depending or lateral portions 5 36, so that each of the parts embrace the sides or surfaces of the flat frame members 11, and thereby not alone a very secure hold is obtained due to certain frictional contact which hold may be augmented by soldering or the like, but the 10 pivotal point of the bag frames is such that the movement of the bag frames in respect to each other results in the least amount of wear upon the hinge. By such correlation of parts the frequent opening and closing of the bag does not 15 cause the hinge to be distorted or broken and in consequence gives long life to the hinge.

Instead of providing for the U-shaped insertions, as shown by 13 in Fig. 2, the base member 10 shown in Figure 4 by the reference character 20 10a, may be turned upon itself as shown by extension 38 and then bent at 39 so that the wall 40 is at right angles to the portion 10a. This member 40 is again bent at right angles so as to form the flange 41 and under the U-shaped 25 member composed of wall 40 and flange 41 and extending portion 42 of the member 10a, the end of the bag with its clip 18, as before described, may be readily inserted and secured therein. For a more fixed security, the flange 41 as also the 30 flange 43 of U-shaped members 13, may be provided with extending tabs 45 as shown in Fig. 4 and in Fig. 2, which tabs are well known, and these tabs are bent over so as to hold the clip 18 in position.

35 From the foregoing it will be seen that my improved bag frame consists in having base members and at the outer edges of the two portions forming these base members, bag-holding structures are provided either in the form as shown 40 in Fig. 2 or in the form shown in Fig. 4; and in either case or in such modification thereof as may occur to any one skilled in this art, the frames 10 are so arranged as to provide space to 45 enable the bag to be filled with desired accessories, such as cigarette case, vanity case and the like, without forcing the bag to bulge or to lose its original shape.

It will also be noted that a novel form of hinge has been provided which is especially adapted for attachment to the particular form of bag frame hereinbefore described.

It is obvious that various changes and modifications may be made in the details of construction and design of the above described embodiments of this invention without departing from the spirit thereof, such changes and modifications being restricted only by the scope of the 10 following claim.

I claim:—

In ladies' handbags comprising complementary frame sections and flexible bag material held thereby forming substantially parallel walls from 15 the frame sections to the bottom of the bag, the combination of flat plates of inverted U-shape, said flat plates being the same in width, length and thickness, the inward edges of which abut each other forming an unbroken exterior surface 20 save for the butt joint therebetween, said flat plates forming the body members of the frames of the aforesaid complementary frame sections, means on the upper exterior surfaces of said plates at the abutting edges thereof for locking 25 said plates together, members one for each plate having a slot engaged by such member, a pivotal connection for said slotted members below both of said plates, a bag material retaining member extending along the length of each of said flat plates at the interior surface and the exterior edges thereof, said retaining members having an open space facing laterally outwardly 30 from the outer edges of the flat plates, the bag material extending therefrom downwardly and inwardly of the outer edges of said flat plates substantially parallel therewith, said retaining members being disposed apart from each other at the interior of the flat plates, and providing a space 35 below the flat plates to enable a cigarette and a vanity case to be positioned within the bag immediately below the bag retaining members and extending within said space without bulging the flexible sides of the bag when the bag is closed.

EDWARD POETER.
